UNITED STATES PATENT OFFICE.

JOSEPH M. MIRAU, OF CROSBY, MINNESOTA.

VEHICLE-CONTROLLED DOOR-OPERATING MECHANISM.

1,216,345.

Specification of Letters Patent. Patented Feb. 20, 1917.

Application filed January 5, 1916. Serial No. 70,400.

To all whom it may concern:

Be it known that I, JOSEPH M. MIRAU, a citizen of the United States, residing at Crosby, in the county of Crow Wing and State of Minnesota, have invented certain new and useful Improvements in Vehicle-Controlled Door-Operating Mechanism, of which the following is a specification, reference being had to the accompanying drawings.

This invention relates to vehicle controlled door operating mechanism and has for its primary object to provide simple and positively operating means primarily actuated by the vehicle to open the door of a garage or similar structure and subsequently permit the door to return to its closed position.

It is another and more particular object of the invention to provide a mechanism of the above character including a spring supported platform extending under the door both interiorly and exteriorly of the structure, air actuated means for moving the door to its open position, and means connected to the platform and actuated upon a depression thereof under the weight of the vehicle to open the air supply whereby the door operating means is actuated.

It is a further general object of the invention to produce a door operating mechanism of the above character, which is exceedingly simple in its construction as well as durable and reliable in practical operation and may be installed at a nominal cost.

With the above and other objects in view, my invention consists in the novel features of construction, combination and arrangement of parts to be hereinafter more fully described, claimed and illustrated in the accompanying drawings, in which,

Fig. 1 is a vertical sectional view through a garage or like structure and the entrance door thereof;

Fig. 2 is a horizontal section taken on the line 2—2 of Fig. 1;

Fig. 3 is a vertical section similar to Fig. 1, illustrating the invention used in connection with another type of door;

Fig. 4 is a vertical sectional view showing an electrical operating means for the door;

Fig. 5 is a detail section taken on the line 5—5 of Fig. 1. Fig. 6 is a detail sectional view of the valve.

Referring in detail to the drawings and more particularly to Fig. 1 thereof, 5 designates the vertical wall of a garage or similar structure having an opening 6 therein for the passage of vehicles, which is normally closed by a vertically movable door 7 mounted for sliding movement in guide channels 8 at the opposite vertical edges of the door opening. These channels extend upwardly into the vertical door receiving channel 9 formed in the building wall above the door opening.

The concrete floor or foundation is recessed, as indicated at 10, said recess extending equal distances from the door opening 6 inwardly and outwardly thereof. In this recess, a depressible platform 11 is arranged and is yieldingly sustained by a plurality of coil springs 12. These springs normally hold the platform with its upper surface above the plane of the concrete base or floor.

A cylinder 13 is suitably mounted within the structure and a piston 15 reciprocates therein, said piston being yieldingly held against movement in one direction by a coil spring 14 arranged within the cylinder between one end thereof and the piston and surrounding the piston rod 15'. This rod extends through a suitable stuffing box in the end of the cylinder and, to the same, a cable or other flexible element 16 is connected. This element passes around guide sheaves 17 and has its other end attached to the top of the door 7. 18 designates a pipe for supplying compressed air to one end of the cylinder 14, said pipe extending from the compressed air tank with which the usual garage is equipped. A three-way valve 19 is arranged in this pipe, said valve being of the ordinary construction as shown in Fig. 6 of the drawing. To the casing of this valve, an inlet pipe P leading to one end of the cylinder is connected, and an outlet pipe P' is also connected to the same end of the cylinder and to the valve casing. P² designates the exhaust pipe connected to the valve casing. The rotary valve member is provided with angularly disposed ports 19^a, 19^b, and 19^c to register with the respective pipes which are connected to the valve casing. The rotary valve member has an arm 20 fixed to one end thereof and a rod 21 is pivotally connected to this arm, the lower end of said rod being connected to the platform 11. It will be understood that the door operating mechanisms are arranged adjacent to the opposite vertical edges of the door so that the door will be properly

100
105
110

raised or elevated by an even upward pull at the opposite edges thereof and the door will not bind in the channels 8.

In the operation of the device above described, when the front wheels of the vehicle move upon the platform 11, as the vehicle approaches the door opening, said platform is depressed against the action of the springs 12; thus pulling the rod 21 downwardly and operating the valve 19 to open the connection between the supply pipe 18 and the cylinder 13. In this position of the rotary valve member, the port 19^a thereof registers with the supply pipe 18, and the port 19^b with the cylinder inlet pipe P, while the port 19^c is closed. Thus, the piston is moved to one end of the cylinder and the cable 16 pulled to draw the door 8 upwardly above the door opening 6 and into the channel or passage 9, thus permitting the vehicle to pass through the door opening into the garage. As soon as the vehicle moves off of the platform 11, the springs 12 will return the platform to its normal position and the rod 21 then actuates the valve 19 to open communication between the cylinder 14 and the atmosphere so that in the downward gravity movement of the door 8 to its closed position, the air will be exhausted from the cylinder 13. The rotary valve member is now disposed in the position shown in Fig. 6 of the drawings, the supply from the pipe 18 being cut off and the port 19^b being in registration with the outlet pipe P' from the cylinder, while the port 19^c registers with the exhaust pipe P. It is thus apparent that the door will immediately close so that a minimum of cold air will enter the garage.

In Fig. 3 of the drawings, I have shown the vertical wall 5 provided with an articulated door of that type commonly found upon roll top desks, the door 8' being made up of a plurality of slats or sections flexibly connected together. This type of door will be used upon small structures and moves in the channel guides 7, the upper ends of which are curved inwardly, as at 7^a, and secured to the side walls of the structure. In this view, I have also shown the vertical rod 21 connected to one arm of the bell crank lever 22, to the other arm of which a rod 23 is pivotally connected, said rod extending from the arm of the three-way valve.

In Fig. 4 of the drawings, I have shown an electrical operating means for the door. This means consists of a motor, indicated at 24, in circuit with a battery or other suitable source of current supply, indicated at 25. To the under side of the platform 11, a contact plate 26 is secured and suitably insulated from the platform to which one side of the circuit is connected. A contact plate 27 is suitably mounted beneath the

plate 26 and connected to the opposite side of the circuit so that when the platform is depressed, said plate 26 will contact with the plate 27 and close the circuit. A suitable switch, indicated at 28', is arranged in the circuit so that the motor 24 may be cut out when it is not desired to operate the door. A driving belt 28 connects the shaft of this motor to a shaft 29 on which a drum 30 is fixed. One end of a flexible cable connected to the door, is attached to this drum and is adapted to be wound thereon in the operation of the motor, whereby the door is elevated to its open position.

From the foregoing description, taken in connection with the accompanying drawings, the construction and manner of operation of the several illustrated embodiments of the invention will be clearly and fully understood. By providing the means primarily actuated by the weight of the vehicle for opening the door, the operator of the vehicle is relieved of the necessity of descending. In cold weather the interior of the garage may be maintained at a comfortable temperature, as the door will immediately close after the vehicle leaves the platform. The invention, with obvious structural modifications, may be readily applied to various types of garages and similar buildings used for the storage of motor vehicles, and can also be readily installed in old structures at relatively small cost.

While I have shown and described the preferred construction and arrangement of the several elements of the device, it will be understood that the invention is susceptible of considerable modification therein and I, therefore, reserve the privilege of adopting all such legitimate changes as may be fairly embodied within the spirit and scope of the invention as claimed.

Having thus fully described my invention, what I desire to claim and secure by Letters Patent is:—

The combination with a structure having a door opening and vertical guides at the opposite sides of said opening, a door vertically slideable in said guides, of a spring supported platform extending substantially the entire width of the door beneath the same and in opposite directions therefrom, a compressed air cylinder mounted above the door when the latter is in open position, a piston to reciprocate in said cylinder, a cable connecting one end of the piston to the upper edge of the door, a spring in the cylinder acting to move the cylinder in one direction, an air supply pipe connected to the cylinder, a rotary three-way valve in said supply pipe having an arm connected thereto, and a rod operatively connected at one end to the platform and extending vertically upward therefrom and having its other end connected to the valve arm where-

by the valve is actuated when the platform is depressed under the weight of a vehicle and communication established between the supply pipe and the cylinder, whereby the 5 piston is moved to elevate the door to its open position, said valve being operated upon the return of the platform to its normal position to open communication between the cylinder and the atmosphere and 10 exhaust the air from the cylinder, whereby

the door is permitted to move by gravity to its closed position, the piston in the cylinder co-acting with the spring to cushion the latter movement of the door.

In testimony whereof I hereunto affix my 15 signature in the presence of two witnesses.

JOSEPH M. MIRAU.
